UNITED STATES PATENT OFFICE.

CARL WALther, OF BERLIN, GERMANY, ASSIGNOR TO GENERAL ELECTRIC COMPANY, A CORPORATION OF NEW YORK.

RAIL-BOND.

SPECIFICATION forming part of Letters Patent No. 687,091, dated November 19, 1901.

Application filed June 27, 1900. Serial No. 21,719. (No model.)

To all whom it may concern:

Be it known that I, CARL WALther, a subject of the Emperor of Germany, residing at Berlin, Germany, have invented certain new and useful Improvements in Rail - Bonds, (Case No. 1,677,) of which the following is a specification.

This invention relates to connectors or bonds for electric conductors designed with especial reference to railroad-rails, but not limited in application to such use.

The object of the invention is to provide a durable bonding device which will afford ample carrying capacity between adjacent rails for the electric current.

Figure 1 is a vertical section of a rail and a bonding device inserted in a hole in the web thereof. Fig. 2 is a side elevation of a part adapted to be inserted in the rail-web, to which part the ends of the bonding-conductor are adapted to be connected. Fig. 3 is an end elevation of the part shown in Fig. 2. Fig. 4 is a plug adapted to be inserted in the longitudinal hole H of the part shown in Figs. 2 and 3, and Figs. 5 and 6 are perspective views showing adjacent rails with the bonding device attached.

The part which is adapted to be inserted in the rail-web is indicated by the letters PS and may be called a "plug-socket," as it has a central hole or perforation H, adapted to receive the plug U. (Shown in Fig. 4.) Each plug-socket is composed of some pliant conducting metal, such as copper or zinc, so that it may be compressed against the hole in the rail-web. If zinc is used, there will be practically no electrolysis, since its electrochemical properties are nearly the same as those of steel. In some cases it may be preferred to use copper, the same metal as that of which the bonding-conductor is composed. Each plug-socket is provided with a flange F to limit its passage through the hole in the rail-web. There are also formed in the external surface of each socket several grooves G of suitable size for the reception of strands S of a copper or other suitable bonding-conductor B. As shown in Fig. 3, the portion of the socket which comprises the wall of the hole H is divided into sections C in order that the socket can be forced against the rail.

This may be in addition to the compressibility of the pliant metal or may be adopted in case a rigid metal is used. After the sockets PS are inserted in the holes in the rail-web, 55 the ends of the strands S being inserted in the grooves G, the plug U, of steel or other suitable metal, is driven into the hole H, whereat the sections C of the wall of the hole H are forced outward against the wall of the hole 60 in the rail-web, and the yielding copper or zinc or other suitable metal of which the socket is composed is compressed against the strands S and against the rail itself, and the strands are also pressed against the rail. The 65 grooves G being originally of just sufficient size to permit the insertion of the strands S are contracted, so that the strands S are tightly inclosed, and it is practically impossible for moisture to enter in. This reduces 70 the liability of electrolytic action, even in case a copper plug-socket is used. The entire contacts of the strands and the socket with the rail and of the strands with the socket thus provide joints with very little re- 75 sistance.

In Fig. 5 the bonds are shown in place, the fish-plate being removed. As shown in this figure, the free ends of the strands H are bent over the flanged end of the socket in order to 80 further guard against their withdrawal from the grooves by expansion.

What I claim as new, and desire to secure by Letters Patent of the United States, is—

1. A rail-bond, which comprises conducting parts, each of which is adapted to be inserted in a hole in the rail, and to be forced against the walls of the hole; a bonding-conductor, each end of which is placed between a rail and one of the conducting parts; and relatively rigid parts, each of which is adapted to force one of the conducting-pieces into intimate contact with its rail and the end of the bonding-conductor.

2. A rail-bond, which comprises conducting parts, each of which is adapted to be inserted in a hole in the rail, and to be forced against the walls of the hole and each of which is provided with a hole, the wall of which is divided into sections; a bonding-conductor, each end of which is placed between a rail and one of the conducting parts; and relatively rigid

- parts, each of which is adapted to force one of the conducting-pieces into intimate contact with the rail and the end of the bonding-conductor.
5. 3. A rail-bond, which comprises plug-sockets of conducting metal, each of which is formed with a longitudinal hole and is adapted to be inserted in a hole in the rail, and to be forced against the walls of the hole; a bonding-conductor, each end of which is placed between a rail and a plug-socket; and relatively rigid plugs, each of which is larger than the hole in a plug-socket, and each of which is driven into the hole in a socket, to force the socket into intimate contact with the rail and with the end of the bonding-conductor.
4. A rail-bond, which comprises plug-sockets of conducting metal, each of which is formed with longitudinal grooves in its external surface and with a longitudinal hole, and is adapted to be inserted in a hole in a rail, and to be forced against the walls of the hole; a stranded bonding-conductor, the ends of the strands of which are placed in the grooves in said plug-sockets; and relatively rigid plugs, which are larger than the holes in the plug-sockets, and each of which is driven into the hole in a socket to force the latter into intimate contact with the wall of the hole in a rail, and with the ends of the bonding-conductor strands.
5. A rail-bond, which comprises plug-sockets of conducting metal, each of which is formed with a longitudinal hole, the wall of which is divided into sections, each plug-socket being formed also with longitudinal grooves in its external surface and being adapted to be inserted in a hole in a rail, and to be forced against the walls of such hole, a stranded bonding-conductor, the ends of the strands of which are placed in the grooves of said plug-sockets; and relatively rigid plugs which are larger than the holes in the plug-sockets, and each of which plugs is driven inside the hole in a socket to force the sections of the wall of the socket into intimate contact with the wall of the hole in the rail and with the strands of the bonding-conductor.
50. 6. A rail-bond, which comprises conducting parts, each of which is adapted to be inserted in a hole in a rail; a bonding-conductor, each end of which is placed between a rail and one of the conducting parts; and relatively rigid parts, each of which is adapted to force one of the conducting-pieces into intimate contact with its rail and the end of the bonding-conductor.
7. A rail-bond, which comprises a stranded bonding-conductor, the ends of which are inserted in holes in the webs of the rails, and each strand of which ends is pressed into intimate contact with the rail.
8. A rail-bond, which comprises conducting-pieces adapted to be inserted in holes in the rail-webs; a stranded bonding-conductor, the ends of which are inserted in the holes in the rail-webs between the rail and one of said conducting-pieces; and means whereby said pieces are pressed against said strands and against the rails.
9. A rail-bond, which comprises a bonding-conductor, plug-sockets of conducting metal, each of which is formed with a longitudinal hole, the wall of which is divided into sections, and with which sockets the ends of the bonding-conductor have intimate electrical contact; and plugs which are larger than the holes in each plug-socket, each of which plugs is driven into the hole in a socket to spread the sections of the wall of the hole in the socket, and force them into intimate contact with the rail.
10. A rail-bond, which comprises a bonding-conductor, plug-sockets of pliant conducting metal, each of which is formed with a longitudinal hole, the wall of which is divided into sections, and with which plug-sockets the ends of the bonding-conductor have intimate electrical contact; and plugs which are larger than the holes in each plug-socket, each of which plugs is driven into the hole of a socket inserted in a rail-web, to spread the sections of the wall of the hole in the socket, and compress them against the wall of the hole in the rail-web.

In witness whereof I have hereunto set my hand this 11th day of June, 1900.

CARL WALTHER.
